UNITED STATES PATENT OFFICE

STACY B. HASELTINE, OF CHICAGO, ILLINOIS, ASSIGNOR TO W. H. MINER, INC., OF CHICAGO, ILLINOIS, A CORPORATION OF DELAWARE

CAR CONSTRUCTION

Application filed December 19, 1929. Serial No. 415,168.

This invention relates to improvements in car construction, and more particularly to means for connecting the body and truck bolsters of railway cars.

5 One object of the invention is to provide a sectional center pin member for connecting the body and truck bolsters of a railway car, of rugged design, having shouldered engagement with the bolsters to prevent separation thereof, wherein the maximum amount of shouldered engagement therebetween is had to provide exceptional tensile strength.

A more specific object of the invention is to provide a center pin for connecting body 15 and truck bolsters of railway cars, comprising a plurality of connecting members including a pair of outer members each having head portions at opposite ends thereof having shouldered engagement with the bolsters 20 respectively, and a central spreading or filler member for holding the sections separated, wherein the spreading member has locking engagement with one of the bolsters to hold the assembled pin against rotation with respect thereto and maintain the head portions 25 in full engagement with the cooperating shoulders of said bolster.

Other objects of the invention will more clearly appear from the description and 30 claims hereinafter following.

In the drawing, forming a part of this specification, Figure 1 is a top plan view of a portion of the body bolster of a railway car, illustrating my improvements in connection therewith. Figure 2 is a vertical sectional view, corresponding substantially to the line 2-2 of Figure 1. Figure 3 is a horizontal sectional view corresponding substantially to the line 3-3 of Figure 2. And 35 Figure 4 is a vertical, transverse sectional view corresponding to a vertical plane at right angles to the sectional view shown in Figure 2.

In said drawings, 10 indicates the body 40 bolster of a railway car and 11 the cooperating truck bolster. The body bolster is provided with the usual spherical bearing member 12 at the bottom thereof, which cooperates with a convex spherical bearing seat 50 13 on a bearing block 14 mounted in a pocket

15 provided at the top of the truck bolster.

In carrying out my invention, I provide the truck and body bolsters with aligned center pin receiving openings 16 and 17 respectively. The openings 16 and 17 are preferably of the same diameter and the bearing block is also provided with an opening 18 aligned with the openings 16 and 17 and corresponding in diameter thereto. The body bolster is provided with a pocket 19 at the 60 top thereof, which is of larger size than the opening 17 of the body bolster, thereby providing a shoulder 20 at the upper end of said opening 17.

The truck bolster is also provided with 65 a pocket 23 which is of larger size than the opening 16 of the bolster, thereby providing a retaining shoulder 24 at the outer end of said opening. The opposed walls of the center pin receiving openings 16, 17 and 18 are 70 also vertically slotted at opposite sides as indicated at 26-26. The slots 26-26 extend through the shoulders 20 and 24 of the body and truck bolsters, thereby cutting away portions of the shoulders and leaving supporting ledges on diametrically opposite sides of the pin receiving openings.

75 My improved center pin proper comprises broadly a pair of outer members A-A and a central filler or spreading member B. The 80 two members A-A are of similar design, each having a shank portion 27 and top and bottom enlargements 28-28. The shank portions 27 of the two members A have flat inner surfaces between which the filler member B 85 is adapted to fit. The outer surfaces of the shank members 27 are curved to correspond with the curvature of the pin receiving openings of the two bolsters. The enlargements 28 are in the form of arcuate flanges which 90 project laterally from the shank portion of each pin member A. The flange portions are of such a size as to be co-extensive with the respective ledge members of the shoulders of the bolsters. By this arrangement, when 95 the two sections A of the pin are spread apart, the enlargements or flanges 28 thereof will register respectively with the ledges of the shoulders of the body and truck bolsters. The enlargements or flanges 28-28 at each 100

end of each member A are of such a size that they will pass through the pin receiving openings of the bolsters when the end portions of said flanges are alined with the slots 26—26 so as to pass through the same. At the upper end, each member A is preferably provided with an eye member to facilitate removal of the same, in a well known manner by employing a hook or any other special tool.

10 The member B is in the form of an elongated plate having laterally enlarged portions 29 and 30 at the top and bottom ends thereof respectively. As most clearly illustrated in Figures 2 and 4, the enlarged portion 29 at the upper end of the member B is of such a height that it extends beneath the shoulder 20 of the body bolster and is of such a width that it occupies the upper end portions of the slots 26—26 of the body bolster. 15 The laterally enlarged section 30 at the bottom end of the member B is located entirely below the shoulder 24 of the truck bolster so that it does not interfere with the relative rotation of the assembled pin and the truck bolster and has the top thereof flush with the enlargements 28—28 at the bottom ends of the members A—A. As will be evident, the enlargements 29 and 30 of the member B 20 and the corresponding enlargements 28—28 and 28—28 of the members A—A together form complete annular head members at both ends of the assembled pin. The member B is also provided with an eye member at the upper end thereof, as most clearly shown in Figures 2 and 4, by which removal of the same is facilitated. At the upper end the member B is thickened as clearly shown in Figure 2, thereby presenting shoulders 31—31 which abut the upper ends of the members A—A for a purpose hereinafter 25 pointed out.

30 In applying my improved center pin to the bolsters of a railway car for connecting the same, the sections A are inserted within the pin receiving openings of the bolsters successively. Each section A while being assembled with the bolsters is placed in such a position that the head portions thereof register with the cut away portions of the shoulders and side walls of the pin receiving openings, the flange forming each head member, as hereinbefore pointed out, being of such a size that it will just clear the walls of the cut away portions of the shoulders and the slots of the side walls of the pin receiving openings. Assuming that the pin member A, shown at the left in Figure 2, is first applied, the same after being fully inserted is displaced laterally outwardly to engage the head portions at opposite ends thereof over the corresponding ledges of the shoulders of the body and truck bolsters.

60 As will be apparent upon reference to Figures 1 and 3, when the member A is thus dis-

placed, the flat inner surface of the same will clear the slots 26—26, so that the other member A may be freely inserted through the pin receiving openings. After the second member A has been applied and fully inserted, the same is displaced laterally outwardly to the right as seen in Figure 2 to bring the head portions thereof in shouldered engagement with the ledges of the truck and body bolster. The filler or spreading member B is then applied by inserting the same between the members A, the member B being entered through the opening at the top of the body bolster. As will be evident, the member B when fully inserted has the enlargement 29 at the top thereof engaging within the upper ends of the slots 26—26 of the body bolster shoulder, thereby locking the assembled pin against rotation with respect to the body bolster. In this connection, it is pointed out that by thus interlocking the parts, the flanges 28—28 at the upper end of the assembled pin are at all times maintained in full engagement with the ledges 20—20 of the body bolster. As hereinbefore pointed out, the shoulders 31—31 of the filler member B, engage the upper ends of the members A—A, thereby holding the member B against downward movement. When the car is operated on curved track, the upper end of the pin being held against rotation with respect to the body bolster, the truck bolster will be rotated with respect to the pin, thereby bringing the enlargement 30 in overlapping relation with the shoulder 24 so that the member B supplements the members A—A in preventing separation of the bolsters, any pull on the enlargement 30 by engagement with the shoulder 24 being transmitted through the shoulders 31—31 thereof to the upper ends of the members A—A and through the flanges of the latter to the shoulder 20 of the body bolster.

65 In removing the pin from the bolsters, the spreading member B is first withdrawn by lifting the same upwardly through the body bolster, one of the sections A then being displaced laterally inwardly so as to register the head portions thereof with the cut away portions of the shoulders and the vertical slots 26. This member may then be withdrawn either through the top of the body bolster or dropped through the bottom of the truck bolster. After removal of this section, the second section A is removed in a similar manner. As will be obvious, the body and truck bolsters may then be freely separated.

70 From the preceding description taken in connection with the drawings, it will be evident that I have provided a composite center pin structure having a shank which entirely fills the center pin receiving openings of the bolsters, thereby providing maximum resistance against shearing action, and have 75 80 85 90 95 100 105 110 115 120 125 130

further provided exceptionally great tensile strength by an unusually great amount of shouldered engagement between the head sections of the pin and the body and truck bolsters.

5 I have herein shown and described what I now consider the preferred manner of carrying out my invention, but the same is merely illustrative and I contemplate all 10 changes and modifications that come within the scope of the claims appended hereto.

I claim:

1. In car construction, the combination with cooperating body and truck bolsters provided with alined center pin receiving openings, each bolster having a shoulder adjacent the outer end of its opening, each shoulder being recessed at diametrically opposite sides, thereby providing spaced ledges; of a pair of 20 connecting members each having a shank and head portions at opposite ends of the shank, said shanks extending through the pin receiving openings of the bolsters; and a spreading member between said first named members 25 for holding the same apart and the head portions thereof engaged with said shoulders, said head portions being of such a size and shape that the same pass freely through the combined space provided by center pin receiving openings and the recessed portion of the shoulders when said spreading member is omitted from between said outer members.

2. In car construction, the combination with cooperating body and truck bolsters provided with alined center pin receiving openings, each bolster having a shoulder at the outer end of its opening, each of said shoulders being recessed at opposite sides of the opening, thereby providing spaced ledges; of 40 a pair of connecting members, each having a shank and head portions at the opposite ends of said shank, said head portions being formed by laterally projecting flanges, said shanks extending through the pin receiving 45 openings of the bolsters; and a central filler member interposed between said first named members and holding the same apart to maintain the shouldered engagement with the ledges of the bolsters, said head portions of 50 each member and the combined cross section of each opening and the recessed portions of the corresponding shoulder being such that said head portions pass freely therethrough when said outer members are applied separately and successively.

3. In car construction, the combination with cooperating body and truck bolsters having alined center pin receiving openings and each bolster having a shoulder adjacent its opening; of a pair of center pin members, each having head portions at opposite ends thereof having shouldered engagement with the shoulders of said bolsters respectively, the shoulders of said bolsters being cut away to 55 clear said head portions of each member while

being applied with the bolsters by separate insertion of each of said members through said openings; and spreading means interposed between said pair of members to hold the same apart and in shouldered engagement with the bolsters, said spreading member being interlocked with one of the bolsters to prevent relative rotation of the assembled pin with respect to said bolster.

4. In car construction, the combination with cooperating body and truck bolsters having alined center pin receiving openings, each bolster having a shoulder adjacent the outer end of its opening, and each shoulder being cut away at diametrically opposite sides, thereby providing a pair of spaced ledges; of a pair of pin members, each having a pair of heads at opposite ends thereof connected by a shank portion, the heads of each of said members having shouldered engagement with said ledges, and each head being co-extensive with one of said ledges, and the shank portion of each member extending through the pin receiving openings of said bolsters, each head being of such a size as to pass freely through the space provided by said pin receiving openings and the cut away portions of the shoulder adjacent to each opening; and a filler member interposed between said first named members for maintaining the shouldered engagement thereof with the shoulders of the bolsters, said filler member interlocking with the cut away portions of the shoulders of one of the bolsters to prevent relative rotation of the assembled pin with respect to said bolster.

5. In car construction, the combination with body and truck bolsters having alined center pin receiving openings, and each bolster having a retaining shoulder adjacent the outer end of its opening, said openings being laterally enlarged at diametrically opposite sides; of a pair of outer members; and a central spreading member, each of said outer members and said spreading member having the enlargements at opposite ends thereof adapted to pass through said openings when alined with said laterally enlarged portions thereof, said enlargements of the outer members and spreading member at each end of the pin together forming complete annular head members at both ends of the pin, the complete annular head member at one end of the pin having shouldered engagement with the shoulder of the corresponding bolster, and the spreading member having shouldered engagement with the outer members at the other end of the assembled pin and the enlargements of said outer members at said last named end of the pin having shouldered engagement with the other bolster.

In witness that I claim the foregoing I have hereunto subscribed my name this 17th day of December, 1929.
